UNITED STATES PATENT OFFICE.

LEANDER R. SPALDING AND GEORGE F. ADAMS, OF NASHUA, N. H.

FOOT-GUARD.

SPECIFICATION forming part of Letters Patent No. 359,899, dated March 22, 1887.

Application filed January 14, 1887. Serial No. 224,373. (No model.)

To all whom it may concern:

Be it known that we, LEANDER R. SPALDING and GEORGE F. ADAMS, citizens of the United States, residing at Nashua, in the county of Hillsborough and State of New Hampshire, have invented certain new and useful Improvements in Foot-Guards for Railway-Frogs; and we do hereby declare that the following is a full, clear, and exact description of the invention, which will enable others skilled in the art to understand it.

Our invention relates to that class of devices intended to prevent the loss of life or limb of the operatives upon our railways.

The object of our invention is to provide a safe and convenient foot-guard for those portions of railway-frogs, guard-rails, and switches, which unavoidably, owing to the necessity of their service, present large openings between track-rails and guard-rails, into which the operators are liable to step, and from which they may not be able to remove their foot in time to avoid a moving train, and thereby lose their life or limb. We attain this object by means of strips of metal placed vertically as to their width in the dangerous openings, these metal plates being held in place by brackets which extend into the throat of the rail, so as to prevent their being lifted from their place, and by being further bolted to a rail or to the road-bed, as may be most convenient. We further provide our foot-guards with spring-brackets in places where they are liable to lateral side displacement from the action of the flange of a car-wheel. We attain these objects by the mechanism illustrated in the accompanying drawings, in which—

Figure 1 shows a rail-frog with our foot-guards in place. Fig. 2 shows a cast-iron frog with our foot-guards in place. Fig. 3 is the foot-guard C removed from the rail and enlarged so as the better to show its construction. Fig. 4 is a rear view of Fig. 3. Fig. 5 is a section of Fig. 1 on line x x. Fig. 6 is a section of Fig. 1 on line x' x'.

As the rail-frog, Fig. 1, and the cast-iron frog, Fig. 2, are familiar to all, and are in constant use all over the country, we will not enter into a description of them.

In the drawings, A represents, in Figs. 1 and 2 the rails over which a car may pass, and B

shows parts of rails which are used as guard-rails. C is a left-hand and D a right-hand foot-guard to be used in a rail-frog. E is a foot-guard extending from the point in Fig. 1 forward. F is a foot-guard in the rear of the point in the same figure. G is a foot-guard extending in the rear of, and H is a foot-guard extending forward of, the point in Fig. 2.

The foot-guards C, D, E, F, G, and H are each of a construction best adapted for the service required in their several locations, and are made of strips of plate metal placed vertically as to their width between the track-rails or track-rail and guard-rail, and are secured in place in a convenient manner adapted to the position of each foot-guard.

C, the left-hand foot-guard, Fig. 1, and shown in Figs. 3, 4, and 5, consists of a metal plate, c, bent at both ends, as shown by c' and c', Fig. 70 3, and are of a width to bring the top of the middle or straight portion on or near a level with the top of the rail, the ends c' c' being made of a less width to allow the flange of a car-wheel to pass over them, their outer ends 75 being formed of the curve and width of the throat of the rail, as shown at c', Fig. 5. The top of C may be bent in a direction from the track-rail, so that any wheel-flange which is imperfect in its action would not be liable to 80 strike its end and so destroy the foot-guard, but would strike the bevel of the bend and cause a lateral displacement of the foot-guard, which, through the action of the spring c', would be returned to its place. Both the springs c' and 85 c' serve to hold the foot-guard firmly in place, their ends being adapted to the curve and width of the rail-throat, as at c', Fig. 5. The part c' of C will preferably be placed against the guard-rail, as shown, making a continuation 90 of the same space between the track-rail and the foot-guard as that between the track-rail and guard-rail.

D, the right-hand foot-guard, Fig. 1, is in most respects the same as C, and is made so 95 as to adapt itself to the other side of the rail. We also show it with the central part bent at both ends, as such a construction may be found desirable in some places.

E, the foot-guard, extending forward from the 100 point, Fig. 1, is a plate of metal held in place at the point by springs e' and e'', and at its other

end is bent, as shown at e^2 , and bolted to the rail. This guard-plate e is of a width which will allow a car-wheel to pass over it, as shown in Fig. 6.

5. F is a foot-guard extending backward from the point in Fig. 1, and consists of a plate of metal, f , having the bend f' . Its top may be on a level with the top of the rails, except at its forward end, f^2 , where it enters into the throat of the rails, and at the rear end, where it is so cut that it may be bolted to the rail-throat, as at f^3 .

The cast-iron rail-frog, Fig. 2, requires foot-guards of a construction the same in principle 15 as those adapted for use on the rail-frog, but of a slightly different form.

G, projecting from the point backward, consists of a plate of metal, the upper edge of which may be of the same height as the track- 20 rail, its rear end being supported by the cross-bar g' , to which it is bolted, and at its forward part it is held in place by the springs g^2 and g^3 .

H is of similar construction to G, except that the plate h does not rise to the level of the 25 track-rail, as in the similar case of e , Fig. 1.

In each of the forms of our foot-guards shown we cut away such portions as are liable to be struck by the flange of a car-wheel, as c' , Fig. 5. To the rear ends of the foot-guards C, D, 30 G, and H we attach stays i , connecting the guards to the road-bed, preventing all backward and forward movement of the foot-guards; and, as they are held from vertical and lateral movement by their own form and the form of 35 the rail and their adjustment thereto, it is obvious they will be securely held in place.

The advantage this form of foot-guard has over any other is that wherever practical the guard rises to a level with the top of the

track-rail, that snow and ice cannot be forced 40 down upon it so as to crush it, and that snow is easily cleared from it.

What we claim, and desire to secure by Letters Patent, is—

1. A foot-guard consisting of a metal plate 45 standing vertically and held by fixed connection to the rail or to the road-bed, so as to divide the space between the track-rail and other track-rails or guard-rails and make it difficult or impossible for a person to get his foot caught in a place so guarded, essentially as described.

2. A foot-guard made of a plate of metal standing vertically, having its ends bent and cut away so as to extend under the space through which the car-wheel flange passes 55 and pressing against and into the throat of the rail and held in position by heavy springs, as shown by C, Fig. 1, essentially as described.

3. A foot-guard made of a plate of metal standing vertically, having one or both of its upper corners bent from the track-rail, as at c' , and securely held in place adjacent to a track-rail, essentially as described.

4. In a foot-guard for railway-frogs, the combination, with a track-rail, of a metal plate standing vertically, being held in place at one end by a spring or springs and at its other end by connection with the track-rail or road-bed, essentially as described.

5. In a foot-guard for railway-frogs, the combination of a track-rail with the guard-plate standing vertically, and the stay-brace i , essentially as described.

LEANDER R. SPALDING.
GEORGE F. ADAMS.
